UNITED STATES PATENT OFFICE.

ERIC ANDERSON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,072,898.

Specification of Letters Patent.

Patented Sept. 9, 1913.

Application filed April 21, 1913. Serial No. 762,661.

To all whom it may concern:

Be it known that I, ERIC ANDERSON, a citizen of the United States of America, and residing at Bridgeport, in the county 5 of Fairfield and State of Connecticut, have invented a certain new and Improved Electric Switch, of which the following is a specification.

My invention relates to electric switch 10 mechanisms and particularly to switches for electric lamp sockets, the object of my invention being to provide a quick make and quick break mechanism of simple construction adapted to effect a wide separation of 15 the contacts and a double break.

In the accompanying drawings, Figure 1 is a vertical section through a lamp socket in which my improved switch mechanism is embodied in one form; Fig. 2 is a longitudinal vertical section through the switch mechanism there shown; and Fig. 3 is a dropped perspective of various switch parts.

The switch mechanism in which my invention is here shown embodied, is arranged 25 in a lamp socket of the same general character and position of line and switch terminals as shown in the copending application of G. W. Goodridge 751,272, and as 30 no claim is made to originality of such arrangement, these parts are for the most part omitted from the drawing. The socket body, here comprising the two insulating buttons A and B of porcelain, is inclosed as usual in the casing comprising cap 5, shell 6 and insulating lining 7. The shell terminal 8 is mounted upon the outer face of the button B and is permanently connected to one of the wire terminals (not shown). The center contact 9, is electrically connected with one of the switch terminals 10, the other being connected to a wire terminal (not shown).

The switch piece comprises a yoke 11, the closed end of which electrically connects the 45 switch terminals 10 in the "on" position of the switch, while the ends of the yoke legs are perforated at 12 to form bearings engaged upon lugs 13 offset from the frame 14. The oscillation of the switch piece is effect- 50 ed by a compression spring 15, bearing at one end against the cross piece of the yoke 11, and at the other end against a slide abutment 16. A guide plunger 17, one end 55 of which passes through the perforation 18 in the yoke carries the spring and rocks at

its other end in the pivoting recess 18^a on the face of the slide 16. Obviously as the slide is moved to shift the head end of the plunger 17 to one side or other of the axis of oscillation of the switch piece on the lugs 13, the pressure of the spring is exerted to oscillate the switch piece one way or the other, as the case may be, and the switch is thus opened or closed with a snap action.

The slide 16 is shifted across the axis of oscillation of the switch piece, in one direction by the cam 19 on the spindle 20 of the switch key 21, the lug 22 on the slide being extended through a slot 28 in the upright 23 of the frame 14 to lie in the path of the cam. The depression of the slide serves to compress a spring 25 which underlies the slide, so that upon a further quarter turn of the key 21, the slide is pressed up again by the spring 25 and the end of the switch spring 15 shifted to a position above the axis of oscillation of the switch piece. A guide pin 24 on the slide retains spring 25 in position.

The lug 26 at the upper end of the slide 80 works in the guide slot 27 in the upright 23 of the frame against which the slide is constantly pressed by the compression spring 15. The extent of vertical movement for the slide is of course limited either by 85 the length of these guide slots 27 and 28, or by the smaller diameter of the cam 19.

The switch spindle 20 is journaled in the uprights 23 and 29 and is secured in any suitable way. A simple method is illus- 90 trated, viz., by mounting the cam on a sleeve 30 of greater diameter than the journal apertures 31, 32 for the spindle which passes through the sleeve 30. A pin 33, passed through the spindle and sleeve, holds the 95 latter together and prevents the accidental withdrawal of the spindle. Various modifications will readily suggest themselves, which do not depart from my invention and I do not limit myself to the details 100 shown.

I claim as my invention —

1. An electric switch mechanism comprising a pivoted oscillating switch piece, a spring suitably connected at one end to said 105 switch piece for operating the latter and a movable abutment for the other end of said spring, a manually operated member and means in connection therewith for shifting said abutment in one direction past the axis 110

of oscillation of said switch piece, and spring means operatively engaging said abutment to shift the latter in opposite direction past the axis of oscillation of said switch piece.

2. An electric switch mechanism comprising a pivoted oscillating switch piece, a spring suitably connected to the free end of said switch piece for operating the latter, a slide abutment for the other end of said spring, a manually operated cam operatively engaging said slide abutment to shift the abutting end of said switch spring past the center of oscillation of said switch piece, and a spring operatively engaging said slide to shift said spring end in the opposite direction past the center of oscillation of the switch piece, substantially as described.
3. An electric switch mechanism comprising a pivoted oscillating switch piece, a spring suitably connected to the free end

of said switch piece for operating the latter, a slide abutment for the other end of said spring, a manually operated cam operatively engaging said slide abutment to shift the abutting end of said switch spring past the center of oscillation of said switch piece, and a spring operatively engaging said slide to shift said spring end in the opposite direction past the center of oscillation of the switch piece, said slide operating spring being placed under operating tension by the movement of the slide under the influence of said cam, substantially as described.

In testimony whereof I have signed my name to this specification, in the presence of two subscribing witnesses.

ERIC ANDERSON.
